(57) **CLAIM**

The ornamental design for portable information terminal, as shown and described.

DESCRIPTION

FIG. 1 is a bottom, front and side perspective view of a first embodiment of a portable information terminal, showing our new design;

FIG. 2 is a top, rear and side perspective view thereof;
FIG. 3 is a bottom, front and side perspective view thereof, shown in an alternate position;

FIG. 4 is a bottom, rear and side perspective view thereof, shown in another alternate position;
FIG. 5 is a front elevation view thereof;

FIG. 6 is a back elevation view thereof;

FIG. 7 is a right side elevation view thereof;

FIG. 8 is a left side elevation view thereof;

FIG. 9 is a top plan view thereof;

FIG. 10 is a bottom plan view thereof;

FIG. 11 is a bottom, front and left side perspective view of a second embodiment of a portable information terminal, showing our new design;

FIG. 12 is a top, rear and right side perspective view thereof;
FIG. 13 is a bottom, front and right side perspective view thereof, shown in an alternate position;

FIG. 14 is a bottom, rear, right side and left side perspective view thereof, shown in another alternate position;
FIG. 15 is a front elevation view thereof;

FIG. 16 is a back elevation view thereof;

FIG. 17 is a right side elevation view thereof;

FIG. 18 is a left side elevation view thereof;

FIG. 19 is a top plan view thereof; and,

FIG. 20 is a bottom plan view thereof.

(Continued)

Design **4** is a portable information terminal including; two housings; a flexible display portion which can be folded inward on front surfaces of the two housings; and two cameras on side surfaces of the two housings, as seen in FIGS. **1-10**.

Design **5** is a portable information terminal including; two housings; a flexible display portion which can be folded inward on front surfaces of the two housings; and a camera on a side surface of one of the two housings, as seen in FIGS. **11-20**.
